WATCH DIAL

Jacques Braconnier, Chatillon-le-Duc, France, assignor to
TMX Sales S.A., Lausanne, Switzerland

Filed Dec. 12, 1973, Ser. No. 426,622

Claims priority, application Switzerland Oct. 26, 1973

Term of patent 14 years

Int. Cl. D10—02

U.S. Cl. D10—124

FIG. 1

FIG. 2

FIG. 3

FIG. 4

FIG. 1 is a front elevational view of a watch dial showing my new design;

FIG. 2 is a rear elevational view thereof;

FIG. 3 is a top edge elevational view thereof;

FIG. 4 is a sectional view as taken from line 4—4 of FIG. 1.

I claim:

The ornamental design for a watch dial, as shown and described hereinabove.
